UNITED STATES PATENT OFFICE.

CHARLES F. PRESCOTT, OF BROOKLYN, NEW YORK, ASSIGNOR TO FRANKLIN RAILWAY SUPPLY COMPANY, A CORPORATION OF DELAWARE.

LATERAL-MOTION DEVICE.

Application filed February 7, 1923. Serial No. 617,442.

To all whom it may concern:

Be it known that I, CHARLES F. PRESCOTT, a citizen of the United States, residing at Brooklyn, in the county of Kings and State 5 of New York, have invented certain new and useful Improvements in Lateral-Motion Devices, of which the following is a specification.

My invention relates to lateral motion devices for the driving or axle boxes of locomotives and other railway vehicles, whether associated with pivoted trucks or with other forms of carriage. The invention has the same general objects and purposes as the 15 construction shown in United States Patent No. 1,181,194, issued to Riegel and Woodard on May 2, 1916, (which may be taken as exemplifying the lateral motion appliances in general use), and is intended to meet the 20 same general conditions. I have here shown and described my invention as adapted and applied to the type of construction shown and described in the application of W. E. Woodard, Serial No. 422,248, filed in the 25 U. S. Patent Office November 6, 1920, now Patent 1,452,862, issued April 24, 1923, under the title "Lateral motion device for driving boxes," assigned to the assignee of this application. Thus applied, my invention 30 gives the lateral motion mechanism greater rigidity and definiteness of action; obviates distortion and injury of parts, reduces wear, and prolongs the useful life of various parts; does away with possibility of lost motion; 35 and allows the weight of the parts to be reduced;—all without sacrifice of any of the advantages of the construction shown in the aforesaid application, such as easy adaptation to new or old locomotives with but 40 minor changes in associated parts, keeping the load central on the driving boxes, and requiring only one of the boxes to deflect laterally at a time.

How these and other advantages can be 45 realized in a novel manner through my present invention will appear from my description hereinafter of the best embodiment of the invention known to me.

In the drawings, Fig. 1 is a fragmentary 50 side view, partly in section, of a railway vehicle axle and its axle boxes, illustrating the application of my present invention thereto, as it would appear from the left of Fig. 2.

Fig. 2 is a view toward one of the vehicle

side frames from the inside, with certain 55 parts in section as indicated by the line 2—2 in Fig. 1, the corresponding wheel of the vehicle being omitted.

Fig. 3 is a side view of a sort of saddle structure appearing in Fig. 2, separated 60 from other parts and on a larger scale than Fig. 2, and partly broken away.

Fig. 4 is a corresponding plan view.

Fig. 5 is a side view of a leverage device 65 or structure appearing in Fig. 2, separated from other parts and on a larger scale than Fig. 2.

Fig. 6 is a corresponding plan view.

Fig. 7 is a corresponding end view.

Referring to Figs. 1 and 2, it will be seen 70 that in the present instance my invention is shown applied to a locomotive in connection with the driving wheels of its "main carriage" (so to term it), rather than with wheels of "accessory carriages" or trucks. 75 The locomotive side frames illustrated are of the standard bar type, with top rails A, bottom rails B, and vertical pedestal jaws C for the vertical movement or play of the driving boxes D. The pedestals C may be provided 80 with the usual shoe and wedge means e and f, or their equivalents, for properly guiding and sustaining the driving or axle boxes D, which rest on the axle G of the driving 85 wheels H. Except as hereinafter described, the parts D, G and H may be of standard or any other suitable type and construction. As shown, the outer and inner flanges i and j of the driving boxes D are spaced apart to afford clearance for such lateral movement 90 of the boxes in the jaws C as is required by the locomotive design and the intended conditions of service, and the outer wear faces of the boxes afford lateral thrust bearing at 95 k for the hubs of the drivers. A due proportion of the load of the vehicle weight, etc., is transmitted to the axle boxes D through the usual spring rigging structure L, and other parts now soon to be described.

In practice, of course, the pedestal jaws 100 C may be closed at the bottom with the usual pedestal frame binder or tie M, and the usual lubricating and other accessory parts may be provided; these latter, however are all omitted from the drawings, to 105 avoid confusion. As shown, the locomotive side frames are interconnected and braced together, both vertically and horizontally,

fore and aft of the axle G, by transverse members or structures N and P, secured to the pedestal jaws C, etc.

In the present instance, the load is transmitted from each spring rigging structure L to the corresponding driving box D at different points lengthwise of the axle G, through a yoke-like saddle 15 whose depending leg portions 16, 17 straddle the top rail 10 A and thus bear on the box D at opposite sides of the frame. The clearance between the saddle 15 and the top rail A permits the saddle to ride up and down (relative to the frame) with the movement of the box D due to inequalities of the track, and the flexibility and looseness at joints of the spring rigging permit the saddle to rock slightly. As shown, the outer saddle leg 16 is the longer, and rests or bears directly on the box D, in a fore and aft seat or socket 18 of appropriate length to take a foot or projection at the lower end of said leg. The shorter inner leg 17 normally bears "solidly" on the box D, as already intimated; but between them extends one end of lever- 25 age means 20 pertaining to the lateral motion device. As here shown, the saddle leg 17 (see, also, Figs. 3 and 4) has feet 21, 21 separated in correspondence with the diameter of the axle G; and in the present instance, it is divided into corresponding fore and aft portions interconnected A fashion, so as to give the saddle yoke 15 as a whole somewhat the character of a tripod. The leverage means 20 (see also Figs. 5, 6, 35 and 7) accordingly comprises, in effect, a pair of bell-cranks with an interconnecting portion 22, shown as of U-shaped cross-section, for the sake of strength and lightness. It is fulcrumed on half-round bearing ridges 23, 23 formed on the bottom of said portion 22, and resting in correspondingly rounded seats in brackets 24, 24 projecting inward from the box D. Thus each 40 of the levers composing the device 20 rests free on the fore and aft fulcrum afforded by its seat on its bracket 24.

As here shown, the double saddle leg 17 rests on the box D through the interposed laterally outward extending arms 25, 25 of the leverage 20. Each saddle foot 21 rests or bears in a fore and aft seat or socket 26 in the corresponding lever arm 25, of appropriate length to take a projection at the bottom of the foot. The other corresponding lever arm 30 extends downward from the fulcrum 23, still to one side of the axle G, and, indeed, substantially in the same transverse plane as the arm 25 and the foot 21. For this depending arm 30 of the lever 20, abutment is provided, to oppose bodily movement of the lever when the box D moves inward under lateral thrust from the corresponding drive wheel H as the locomotive takes a curve with this

wheel toward the outside. As shown, such abutment is afforded by a substantially flat thrust or bearing shoulder 31 at one end of a lateral protuberance on the corresponding cross-brace member N or P, and the lower end of the lever 30 presents an appropriately angled face at 32 to cooperate with such shoulder.

In the embodiment of my invention here illustrated, the construction at the opposite sides of the vehicle carriage is all exactly alike.

Fig. 1, especially, shows the normal positions of the parts when the device is properly adjusted and the locomotive is on straight track. The hubs of the wheels H, H abut against the wear faces k, k of the boxes D, D; the arms 25 of all four of the centering levers 20 rest on the boxes; the spring saddle 15, 15 are upright, with both arms bearing solidly on the boxes; all four of the lever arms 30 are practically in working contact with the fixed thrust shoulders 31 on the locomotive frame; and there are clearances between the outer axle box flanges i at both sides of the carriage on the one hand and the corresponding shoes and wedges e, f on the other hand, while the inner flanges j at both sides are practically in contact or engagement with said shoes and wedges.

If, now, the vehicle takes a curve with the left-hand wheel H at the outside, the resulting lateral thrust on and from this wheel will shift or displace the left-hand box D inward, to the right, carrying the lower ends of the corresponding saddle legs 16, 17, the fulcrua 23, and the two levers 20 as a whole bodily with it. The right hand box D will not, however, be affected; on the contrary the axle G will slide freely through it the amount of the deflection,—the more easily because when deflection occurs the axle is already revolving in the box, so that there is no "friction of rest" to be initially overcome. Inward lateral movement of the lower ends of the lever arms 30 being opposed by the abutment or thrust shoulders 31, such movement of the left-hand box D and the fulcrua 23 will rock the levers 20 and raise their arms 25 and the inner saddle leg 17 against the load of the vehicle weight,—thus acting to rock the saddle 15 outward, to the left, and lift the load. With proper proportioning of the parts, the inward movement of the saddle legs 16, 17 with the box D, as above described, and the tendency of the top of the saddle 15 to move outward as the saddle rocks will balance or compensate one another,—so that actually the upper part of the saddle that carries the spring rigging will not shift laterally at all with reference to the locomotive side frame, but merely "twist" or tilt to a slight extent, easily permitted by the usual flexibility and

- looseness of the rigging L. As soon as the vehicle passes from the curve to tangent track and the lateral thrust on the box D is thus relieved, the load acting through the 5 saddle leg 17 will force the arm 21 down again, thus actuating the lever 20 to return the box D to its original position. And when the vehicle takes a reverse curve, a similar action will occur at the other side.
- 10 It will be seen that inasmuch as the saddle legs 17 bear on the arms 25 of the leverage devices 20 substantially in the transverse plane of the arms 30, and also (in part) directly over the bracket seats 24, 24 of the 15 fulcra 23, 23, approximately in such plane, there is no torsional stress or strain in the interconnecting member 22, and practically no vertical bending stress. This difference from the construction shown in the above- 20 mentioned Woodard application,—in which the inner saddle leg bears on a single lateral arm directly over the center of the axle, so as to impose torsional and even transverse bending stresses on the connecting member 25 22,—not only makes the device 20 perfectly rigid in action and obviates all danger of distortion or breakage of its interconnecting member, which might give rise to lost motion and render the device more or less in- 25 operative or ineffective, but also allows the member 22 to be made relatively light, since the rockers at its ends are in effect almost independent of one another. Also, the saddle yoke 15 is strong without requiring 30 to be heavy, and has a broad fore and aft “base” at its inner side (represented by the distance apart of its feet 21) to prevent its ever being overturned fore and aft.
- I claim:
- 40 1. A railway vehicle lateral motion device comprising an axle box; a cooperating leverage device with arm extending downward from its fulcrum; and means for transmitting the load to said leverage device bearing 45 on the latter substantially in the plane of the rocking movement of said arm.
2. A railway vehicle lateral motion device comprising an axle box, a lever fulcrumed at the inner side of said box, with 50 an arm extending from said fulcrum to carry the load of the vehicle weight and an arm extending downward in substantially the same transverse plane as said first-mentioned arm, and means for opposing movement of said latter arm with lateral movement of the box, so as to rock the lever and raise said first-mentioned arm against the load aforesaid.
3. A railway vehicle lateral motion device comprising an axle box with fore and aft fulcrum means at its inner side, a lever resting free on said fulcrum means, with an arm extending therefrom to carry the load of the vehicle weight and an arm extending downward in substantially the same 60 plane as said first-mentioned arm, and means for opposing movement of said latter arm with lateral movement of the box, so as to rock the lever and raise said first-mentioned arm against the load aforesaid. 70
4. A railway vehicle lateral motion device comprising an axle box and a saddle straddling the frame above the axle box with legs for transmitting the load to the latter outside and inside of the frame, and feet on the inside leg for transmitting its share of the load at opposite sides of the axle. 75
5. A railway vehicle lateral motion device comprising an axle box; a cooperating leverage device; and means for transmitting the load to said leverage device bearing on the latter at opposite sides of the axle. 80
6. A railway vehicle lateral motion device comprising an axle box; a cooperating leverage device with arms extending downward to either side of the axle; and means for transmitting the load to said leverage device bearing on the latter substantially in the transverse planes of the aforesaid arms. 85
7. A railway vehicle lateral motion device comprising an axle box; a leverage device fulcrumed on said box with arms extending downward at either side of the axle, and means for opposing movement of said arms with lateral movement of the box, so as to rock the leverage device; and a saddle straddling the frame above the axle box having legs for transmitting the load to the latter outside and inside the frame, and bearing on said leverage device substantially in the transverse planes of the aforesaid arms. 95
8. A railway vehicle lateral motion device comprising an axle box; a saddle straddling the frame above the axle box with legs for transmitting the load to the latter outside and inside of the frame, and feet on the inside leg for transmitting the load at opposite sides of the axle; a leverage device fulcrumed at the inner side of the box, with arms extending outward to engage said feet and carry the load of the vehicle weight, and arms extending downward in substantially the same transverse planes as said first-mentioned arms; and means for opposing movement of said latter arms with lateral movement of the box, so as to rock the leverage device and raise the inside saddle leg against the load aforesaid. 100
9. A lateral motion leverage device having means for fulcruming the same on an axle box, an arm for extending downward from said fulcrum means, and bearing for receiving the load of the vehicle weight located substantially in the plane of rocking of said arm. 115
10. A lateral motion leverage device having means for fulcruming the same on an 120
11. A lateral motion leverage device having means for fulcruming the same on an 125
12. A lateral motion leverage device having means for fulcruming the same on an 130

axle box, downward extending arms separated lengthwise of said fulcrum means, and bearings for receiving the load located approximately in the planes of movement 5 of said arms.

11. A saddle yoke for straddling a vehicle frame and transmitting the load of the vehicle weight, having at one side a foot for bearing on the axle box and at its other 10 side separate feet for bearing on lateral motion means.

12. A saddle yoke for straddling a vehicle frame and transmitting the load of the vehicle weight, having at one side a foot for

bearing on the axle box and at its other 15 side feet separated in correspondence with the diameter of the axle for transmitting the load to lateral motion means at either side thereof.

13. A tripod saddle for straddling a vehicle frame and transmitting the load of the vehicle weight to an axle box at one 20 side of the latter and to lateral motion means at separated points at its other side.

In testimony whereof, I have hereunto 25 signed my name.

CHAS. F. PRESCOTT.
